UNITED STATES PATENT OFFICE.

OLIVER H. BARDON, OF CINCINNATI, OHIO.

MANUALLY-OPERATED SWITCH STAND.

Application filed November 25, 1921. Serial No. 517,669.

To all whom it may concern:

Be it known that I, OLIVER H. BARDON, a citizen of the United States, residing at Cincinnati, in the county of Hamilton and 5 State of Ohio, have invented new and useful Improvements in Manually-Operated Switch Stands, of which the following is a specification.

My invention relates to manually operated 10 parallel ground throw switch stands for use on railways and to the connections between said stands and the switch point rails. Such stands have a target shaft with targets for use by day and a lantern with 15 colored lights for use by night.

A very dangerous feature in most of the latched switch stands now in use is, that, when a switch is "run through", the force of the flanged wheel forcing its way between 20 the points, causes the latch or lock to release the throwing lever which returns to its former, or open, position with tremendous force, thereby endangering life and limb, and sometimes hurls off fragments of metal 25 due to the force with which the lever enters the latch or lock on the opposite end of the stand.

One object of my invention is to provide 30 a switch stand that will remain automatically locked from the rail end of the device when the throwing lever is in either of its horizontal positions, rendering unnecessary the use of locks or latches. Locks or latches are and must be used on practically all of 35 the types of switch stands in general use.

Another object of my invention is to provide 40 a switch stand equipped with a cheaply and readily renewable element having a frangible part which element is securely held against accidental displacement by the fork of the connecting rod; and the frangible portion of said element has sufficient cross-sectional area to withstand the strain of normal traffic; but will automatically shear 45 off when subjected to the abnormal strain caused by the spreading of points and "run throughs."

Another object of my invention is to provide 50 a switch stand in which the levers are so arranged and constructed that the labor of operating the switch is reduced to little more than the force necessary to lift the weighted lever from horizontal to vertical position. When the weighted lever passes 55 vertical or neutral position, it will fall by

gravity to the opposite horizontal position and in so doing change the position of the switch points through the levers and cranks hereinafter described.

Another object of my invention is to provide 60 the maximum amount of protection for the working parts against snow and ice in winter and rain and dirt in summer.

Another object of my invention is the elimination of bolts, nuts and cotter pins, 65 which become lost, and gears, racks and springs, which cause lost motion, and all of which contribute largely to inefficient operation and high cost of maintenance of 70 switch stands now in use.

My invention provides a switch stand of few and simple parts, with resulting economy of manufacture and replacement upon breakage, and of great ease of operation and reliability of performance, for both opening 75 and closing movements are positive. The complete switch stand will weigh about 65 or 70 pounds. The element with the frangible part is so small that it will lie in the palm of the hand and weighs about four 80 ounces. The parts require very little machine work and the operations are simple. These facts are mentioned to emphasize the 85 points just above mentioned.

My invention is illustrated in the accompanying drawings, in which:—

Figure 1 is a perspective of my switch stand in position for use, the switch which it operates and the adjacent tracks,

Fig. 2 is an enlarged top plan view of my 90 switch stand with the cap removed showing the levers and cranks and their relation to the operation of the mechanism,

Fig. 3 is an enlarged front elevation of the device showing the normal working position of the stand between ties with the working parts dotted in,

Fig. 4 is an enlarged vertical section on the line 4—4 of Fig. 3 as though shown there in full, showing working parts of the 100 device in elevation.

Fig. 5 is an enlarged section on the line 5—5 of Fig. 2, and

Fig. 6, an enlarged detail, is a perspective of the renewable element with its frangible 105 part.

Referring now to the drawings; A is the supporting housing upon which the working parts rest, and it is hung upon and seated between the ends of two contiguous rail- 110

road ties extended for the purpose. A¹ is the housing cap which seats upon A protecting the working parts.

B is the throwing lever which is used to 5 operate the switch stand. It has weight b, handle b¹, short bearing shaft b², crank b³, and lug or pin b⁴ adapted to reciprocate the L-shaped sliding element D as more fully described hereinafter. When the lever B is 10 in either horizontal position, the pin b⁴ is on dead center in the slot d, so that no matter how much force is exerted from the switch it will not throw the lever.

A travel bar C resting in recesses in the 15 casing A has the L-shaped sliding element D mounted upon it and said crank is adapted to travel lengthwise of said bar. The L-shaped sliding element D has a vertical slot d in which the pin b⁴ operates to shift 20 said L-shaped sliding element, and a rearwardly extending arm d¹, with a lug or pin d² upon the upper side of the end thereof.

A connecting crank E formed as a bell-crank lever, has through one of its arms a 25 vertical slot e, longitudinal of said arm, in which the pin d² operates. At the outer end of the other arm of the connecting crank E is a vertical recess e¹ with relatively narrow outer portion or neck and enlarged 30 inner portion adapted to receive and securely hold the projecting frangible part f of the renewable element F. The connecting crank E is pierced vertically at its elbow by a squared hole e² in which seats a 35 squared portion of the target shaft G. On its under side the connecting crank E has a boss e³ which seats in a vertical hole a, through a boss a¹ on the inside of the supporting housing A, forming a bearing for 40 said connecting crank.

The renewable element F has a vertical hole f¹ adapted to receive a pin h which connects the forked end h¹ of the connecting rod H with the replaceable element F.

45 The fork h¹ prevents the frangible part f from leaving its seat e¹ in the connecting crank E.

The connecting rod H is connected with the switch points in the usual way. The 50 target g and lantern support g¹ are of the present well known construction.

I do not limit myself to the precise structure shown, but obviously many changes may be made and any device that will read upon 55 the claims or any of them is within the scope of my invention.

The operation of the device is as follows: The weighted throwing lever B is lifted from whichever horizontal position it is at 60 the time, carried past the vertical position and released, whereupon it drops to the opposite horizontal position. In so doing the pin b⁴ shifts the intermediate crank D lengthwise of the travel bar C. This causes 65 the pin d² to shift the lever E, and through

it to shift the connection rod H to open or close the switch as the case may be, and at the same time to rotate the target g a one-fourth turn.

I claim as my invention and desire to 70 secure by Letters Patent of the United States, the following:—

1. A manually operated switch stand comprising essentially the combination of a throwing lever, a travel bar, an L-shaped 75 sliding element adapted to be moved lengthwise on said travel bar by said throwing lever, a connecting crank, means for transmitting movement from said L-shaped sliding element to said connecting crank to oscillate the latter, a replaceable member constituting in effect an extension of the outer arm of said connecting crank, a recess in said arm of said connecting crank and a frangible extension on said replaceable element for connecting said replaceable element with said connecting crank, a connecting rod, adapted to throw the switch, said connecting rod pivoted to said replaceable element, a bearing on said connecting crank intermediate its said connections and a target shaft at said bearing adapted to be rotated by the oscillation of the connecting crank.

2. A manually operated switch stand having in combination, a throwing lever, a pin on said throwing lever, a travel bar, an L-shaped element with a vertical and a horizontal arm, said element reciprocable on said travel bar, and having a vertical slot in said vertical arm into which said pin extends to produce said reciprocation upon movement of said throwing lever, a substantially vertical lug on said horizontal arm, a connecting bell crank lever pivoted at the elbow, a slot in one arm of said connecting 105 crank to engage said lug and by which lug said connecting crank is oscillated, a recess in the end of the other arm of said connecting crank, a renewable element constituting an extension of said arm with a head 110 adapted to seat in said recess, and a connecting neck of such proportions as to be broken by abnormal strains thereon exerted from the switch to be controlled by said stand, a hole through the outer portion of 115 said renewable element, a connecting rod pinned through said hole to the renewable element at one end and to the switch to be thrown at the other, and a bearing for said connecting crank intermediate its ends and 120 a target shaft secured to said connecting crank at said bearing, and adapted to be rotated by the oscillation of said connecting crank.

3. A manually operated switch stand having in combination, a throwing lever having a pin engaged in a vertical slot in an L-shaped sliding element and adapted to reciprocate said L-shaped sliding element, said pin being on dead center at either horizontal 125

130

position of said throwing lever, said L-shaped sliding element seated upon and adapted to travel lengthwise of a travel bar, a substantially horizontal arm of the L-shaped sliding element with a substantially vertical lug on said arm, a connecting crank with a substantially longitudinal slot on one end, in which slot the vertical lug seats to oscillate said connecting crank, a recess in the other end of said connecting crank, a renewable element one portion of which is adapted to seat in said recess so as to cause said renewable element to constitute an extension of said arm, and having a frangible portion adapted to be broken by abnormal strains thereon exerted from the switch to be controlled by said stand, a hole through the outer portion of said renewable element, a connecting rod pinned through said hole to the renewable element at one end and to the switch to be thrown at the other, and a bearing for said connecting crank intermediate its ends and a target shaft secured to said connecting crank at said bearing, and adapted to be rotated by the oscillation of said connecting crank.

4. A manually operated switch stand having in combination, the throwing lever B, the L-shaped sliding element D adapted to be pushed lengthwise of the travel bar C by the lever B, the connecting crank E adapted to be oscillated by the movement of

the L-shaped sliding element D, the renewable element F with a frangible part forming an extension of the throwing arm of the connecting crank E, the connecting rod H secured to the switch to be thrown at one end and the renewable element F at the other, a target seated upon the connecting crank E and rotated by its oscillation, and elements B, C, D and E resting upon the supporting housing A, and adapted to be lifted therefrom to disassemble said device.

5. In combination with a switch stand of the character indicated, a switch throwing crank, a renewable element adapted to constitute an extension of one arm of said crank, a connecting rod pivoted to said renewable element, and a frangible part of said renewable element adapted to connect said renewable element with the end of said arm of said switch throwing crank so that when an abnormal strain is put upon the switch it will be transmitted through said connecting rod and break said frangible part.

In testimony whereof I have hereunto set my hand in presence of two subscribing witnesses.

OLIVER H. BARDON.
